(No Model.)

C. S. DEAN.
WATER TUBE CLEANER.

No. 580,774.

Patented Apr. 13, 1897.

UNITED STATES PATENT OFFICE.

CYRUS S. DEAN, OF FORT ERIE, CANADA, ASSIGNOR TO WILLIAM B. PIERCE,
OF SAME PLACE.

WATER-TUBE CLEANER.

SPECIFICATION forming part of Letters Patent No. 580,774, dated April 13, 1897.

Application filed September 9, 1896. Serial No. 605,238. (No model.)

To all whom it may concern:

Be it known that I, CYRUS S. DEAN, a subject of the Queen of Great Britain, residing at Fort Erie, in the county of Welland and Province of Ontario, Canada, have invented certain new and useful Improvements in Water-Tube Cleaners, of which the following is a specification, reference being had therein to the accompanying drawings.

10 The incrustation, scale, deposits, and accumulations upon the inner side of water-flues of steam-boilers interfere materially with their heat conductivity, consequently requiring a greater consumption of fuel to maintain 15 the steam at a given pressure and otherwise detracting from the efficiency of the boiler; hence the desirability of removing such deposits and incrustation. Chemicals and mechanical appliances have been resorted to for 20 loosening and removing the obstructing matter, and give more or less satisfactory results, the reagents being slow in their action and the mechanical appliances operating fairly well when the scale is comparatively soft, 25 but failing when the incrustation is hard and smooth.

This invention aims to provide a tool which will operate after the principle of a chisel and hammer, this being the most effectual 30 way known for removing the incrustation from large surfaces, but which is not practiced for water-tubes because of the confined space not admitting of such operation.

The vital feature of the invention is a cutter 35 which is vibrated rapidly, either by an oscillating or a reciprocating motion, and caused to impact against the sides of the water-tube and chip the scale and incrustation therefrom, the loosened scale being driven 40 off by the blast employed for actuating the cutter, and means for driving the cutter through the instrumentality of steam, compressed air, or like medium.

In its organization the tool comprises, essentially, a head having a chamber, a piston operating within the chamber and having the cutter connected therewith, inlet and exhaust ports communicating with the aforesaid chamber, and a valve controlled by the 45 piston for regulating the admission and ex-

hausting of the motive medium from the chamber.

For a full understanding of the merits, advantages, and details of the invention reference is to be had to the following description 55 and the accompanying drawings, in which—

Figure 1 is a longitudinal section of the tool and a water-tube, showing the invention applied, the intermediate portion of the tube and the operating-pipe being broken away. 60 Fig. 2 is a longitudinal section of the head portion of the tool at right angles to Fig. 1. Fig. 3 is a rear end view of the head. Fig. 4 is a front end view of the head. Fig. 5 shows the cutter differently connected with 65 the piston.

In the following description and in all the views of the drawings corresponding and like parts are referred to and designated by the same reference-characters.

The tool comprises a head 1 and a shell 2, the head being secured within one end of the shell in any convenient and substantial way so as to admit of its removal for repairing, inspecting, or other desired purpose. The 75 rear end of the shell 2 is closed by a cap 3, and tie rods or bolts 4 pass through corresponding openings 5 in the said cap and head to secure the parts in fixed relation. The operating-pipe 6 is adapted to be connected 80 with the cap 3 in the usual manner and is in communication with the means for supplying the steam, compressed air, or other medium for operating the tool.

The pipe 6 may be advanced in the ordinary 85 way, but by reason of the peculiar construction of the tool it is necessary to turn it at the same time while advancing the tool within the water-tube, and in order that the tool may be advanced and turned regularly, so as not 90 to miss any portion of the tube-surface to be cleaned, it has been found expedient to devise a mechanism for attaining this end, and, as shown, this mechanism consists of a bearing-block 7, fitted into the opening in the 95 outer wall of the boiler opposite the tube to be cleaned, said block having a nib or projection 8 and an exteriorly-threaded pipe 9, slidably mounted upon the pipe 6 and having a hand-wheel 10 at its outer end for turn- 100

ing the said feed-pipe and the pipe 6, the latter being held fast by a binding-screw 11, bearing at its inner end against the side of the pipe 6. The nib or projection 8 enters the 5 thread or spiral groove of the feed-pipe 9. Hence upon turning the latter by means of a hand-wheel 10 the pipe 6 and the tool attached thereto will be simultaneously turned and advanced within the water-tube 12. The 10 feed-pipe 9 is much shorter than the water-tube, and when advanced to the limit of its movement it is loosened and moved outward upon the pipe 6 and again secured thereto by retightening the binding-screw 11, which was 15 previously loosened. This operation is repeated until the tool has traversed the entire length of the water-tube, after which the tool is withdrawn to be applied in the same manner to another tube.

20 The head 1 is formed with a transverse chamber 13 between its ends, exhaust-ports 14 and 15, and ports 16, the latter serving both as inlet and exhaust ports. These several ports communicate with the chamber 13.

25 A piston 17 fits snugly within the chamber 13 and reciprocates therein and is reduced between its ends, as shown at 18, to provide an annular space for the escape of the spent steam or other motive medium. A lever 19 is fulcrumed to the head within the opening 15 and extends through a transverse opening in the piston and projects a short distance beyond the rear end or face of the head 1 to engage with a slide-valve 20 for operating it 30 to control the entrance of the motive medium into and the exhausting of the spent motive medium from the chamber 13.

The slide-valve 20 fits against the rear face of the head 1 and is held in place by a cap 21, 40 which is secured to the head and has inner projections or lugs 22, between which the rear end of the lever 19 operates, said lugs being spaced apart to allow a limited movement of the piston prior to shifting the valve.

45 The lever 19 extends beyond the front end of the head and carries the cutter 23, which is mounted upon the tapering end of the said lever and held in place by jam-nuts 24 and a pin 25, the latter serving to prevent the 50 turning of the cutter upon the lever. The opening through the cutter tapers to conform to the tapering end of the lever 19, and the said cutter is forced home upon the lever by the action of the jam-nuts 24, thereby securing 55 a substantial connection between the parts. The active or cutting ends of the cutter may have any desired form of edge found most advantageous, according to existing conditions, and, as shown, the ends are pointed, 60 as in practice this form has been found to give the best results.

A ring 26 is secured to the front end of the head 1 and has an outwardly-flaring rim 27, between which and the shell 2 is formed an 65 annular space 28, which contracts at its outer end, forming in effect an annular nozzle to

direct a blast of steam, compressed air, or other medium against the inner side of the water-tube, so as to remove the detached 70 crustation and carry the same off. The outward flare of the rim 27 causes the jet to strike the side of the water-tube. Ducts or 75 passages 29 extend through the head and communicate with the annular space 28 and convey the motive medium from the interior 80 of the shell 2 to the said space 28.

The operation of the tool may be briefly stated as follows: The steam or other motive medium being conveyed to the interior of the shell 2 passes therefrom into the chamber 13 80 through a port 16 and drives the piston from one end of the chamber to the other, the air in the rear of the piston escaping through the other port 16 into the valve 20, and thence out through the port 15, annular space 18, and 85 port 14. An instant prior to the piston reaching the limit of its stroke it closes the port 16 previously exhausting, and if no means were provided to cause a rebound of the piston the position of the slide-valve would remain unchanged and the tool would be inoperative for the purpose designed, and to overcome this difficulty springs 30 are located at the ends of the port 14, so as to engage with the lever 19 and move it and the piston to 90 uncover the port 16 previously exhausting and shift the slide-valve so that the steam may enter the said port and drive the piston in the opposite direction, the port 16 first admitting the steam now serving to exhaust, 95 and the operation of reversing the valve will 100 be repeated, thereby reciprocating the piston and actuating the cutter connected therewith. By having the loose connection between the lever 19 and the valve 20 the piston will 105 move so as to uncover the port prior to shifting the valve for admitting the steam into the chamber 13 behind the piston. The springs 30 are disposed so as to be compressed prior to the cutter striking the tube and before the 110 piston reaches the limit of its stroke, whereby upon regaining themselves the end herein described will be attained. The springs 30 are 115 only of advantage in starting, as after the tool is in operation the rebound of the cutter and the compressing action of the steam within the chamber 13 serve to move the piston sufficient to uncover the port and shift the valve.

The cutter may be connected with the piston in various ways, either directly, as shown 120 in Fig. 5, or indirectly, as shown in Fig. 1, and as illustrated in Fig. 5 the ends of the piston are extended, as shown at 31, and operate through openings in the side of the head and receive a cutter 32, and the lever 19^a is shortened 125 and does not extend through the piston, but engages therewith simply, so as to effect a shifting of the valve. Annular grooves are provided in the end of the piston around the tubular extensions 31 and receive springs 33 130 to effect the purpose for which the springs 30 are provided. The operation of this tool does

not differ from that herein described. Hence it is deemed not to be necessary to set forth the same.

From the foregoing it will be understood that various changes in the form, proportion, and minor details of construction may be resorted to without departing from the spirit of the invention.

Having thus described my invention, what I claim, and desire to secure by Letters Patent, is—

1. In a water-tube cleaner, the combination of a chambered head, a piston adapted to reciprocate in the said chamber, a lever fulcrumed to the head and carrying a scale-loosening device and having connection with and operated by means of a piston, and means for admitting steam or other motive medium into the chamber upon opposite sides of the piston to drive the latter positively in each direction and controlled by the said piston, substantially as described.

2. In a water-tube cleaner, a chambered head having inlet and exhaust ports, a valve for controlling the said ports, a piston adapted to reciprocate in the chambered head, a connection between the valve and piston for shifting the said valve, and a lever fulcrumed to the head and bearing a scale-loosening device and having connection with and vibrated by means of the said piston, substantially as set forth.

3. In a water-tube cleaner, a chambered head having inlet and exhaust ports, a slide-valve for controlling the ports, a piston adapted to reciprocate in the head and alternately close the ports, a lever bearing a scale-loosening device connected with and vibrated by the piston, and a connection between the piston and slide-valve for shifting the latter, and having a limited play whereby the piston will uncover an inlet-port prior to shifting the valve for closing the said port, substantially as set forth.

4. In a water-tube cleaner, a chambered head having inlet and exhaust ports, a piston adapted to reciprocate within the head and alternately close the ports, a lever connected with and vibrated by means of the piston, and bearing a scale-loosening device, and a slide-valve for controlling the said ports, and having inner extensions, to receive the inner end of the aforesaid lever, substantially in the manner set forth for the purpose described.

5. In a water-tube cleaner, a chambered head having inlet and exhaust ports, a piston adapted to reciprocate within the head, and alternately close the ports, a scale-loosening device connected with and operated by means of the piston, a lever fulcrumed to the head and having connection with the piston, and a slide-valve for controlling the ports and having inner extensions between which the opposite end of the lever has a limited play, substantially as and for the purpose set forth.

6. In a water-tube cleaner, a chambered

head having ports, a piston operating in the head, and alternately closing the ports, a scale-loosening device connected with and operated by means of the piston, a slide-valve for controlling the inlet and exhaust ports and actuated by means of the said piston, and springs for positively moving the piston at the end of its stroke, substantially as and for the purpose set forth.

7. In a water-tube cleaner, a head having a transverse chamber between its ends, and having ports extending through the ends of the head and communicating with the chamber, a piston adapted to reciprocate within the chamber and alternately close the inlet-ports and reduced midway of its ends to provide an annular space, a scale-loosening device connected with and operated by means of the piston, and a slide-valve for controlling the ports and operated by means of the piston, substantially as set forth.

8. In a water-tube cleaner, a chambered head having inlet and exhaust ports, a piston adapted to reciprocate within the head, a cutter, a slide-valve for controlling the said ports, and a lever fulcrumed to the head and having engagement with the slide-valve and piston and carrying the said cutter, substantially as set forth.

9. In a water-tube cleaner, a head having a transverse chamber, openings leading from the chamber through the ends of the head, and having inlet-ports, a piston adapted to reciprocate in the chamber and alternately close the inlet-ports, a slide-valve, and a lever bearing a cutter and fulcrumed to the head and operating in the end openings thereof, and engaging with the said slide-valve and piston, substantially as and for the purpose described.

10. In a cleaner of the character described, a head provided with the cutting mechanism and having longitudinal ducts, and a ring secured to the head and having an outwardly-flaring rim forming an annular space, which space is contracted at its outer end to provide a nozzle for facilitating the cleaning operation, substantially in the manner specified.

11. In a tube-cleaner, the combination of a chambered head, a pivoted scale-loosening device, a slide-valve for controlling the admission and exhausting of steam or other motive medium from the chamber, and a piston located in the chamber and reciprocating therein and adapted to positively actuate the scale-loosening device and slide-valve, substantially in the manner set forth for the purpose specified.

12. In a tube-cleaner, the combination of a chambered head having inlet-ports communicating with the end portions of the chamber, a scale-loosener, a piston for actuating the scale-loosener located in the chamber of the head and adapted to alternately close the inlet-ports, and a slide-valve operatively connected with the piston and adapted to act

jointly therewith for controlling the proper admission of the motive medium into the chamber for driving the piston, substantially as set forth.

- 5 13. In a tube-cleaner, the combination of a chambered head having ports communicating with the end portions of the chamber, a scale-loosener, a piston for operating the scale-loosener located in the chamber and adapted to
10 alternately close the inlet-ports, a slide-valve acting jointly with the piston for controlling the inlet-port, and a vibrating connection be-

tween the piston and slide-valve and admitting of the latter parts having a limited play whereby an inlet-port is closed by the piston prior to being uncovered by the slide-valve, substantially as and for the purpose set forth. 15

In witness whereof I have hereunto signed my name in the presence of two subscribing witnesses.
